UNITED STATES PATENT OFFICE.

ALVA A. LOOMIS, OF EMPIRE, OHIO.

BOOK-SHELF AND SHIPPING-CRATE.

SPECIFICATION forming part of Letters Patent No. 700,060, dated May 13, 1902.

Application filed May 7, 1901. Serial No. 59,178. (No model.)

To all whom it may concern:

Be it known that I, ALVA ALBERT LOOMIS, a citizen of the United States, residing at Empire, in the county of Jefferson and State of Ohio, have invented certain new and useful Improvements in Book-Shelves and Shipping-Crates; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to shipping-boxes, and has for its object to provide a device which will insure the safe transportation of books and which may be readily converted into a book case or shelf of neat and artistic 20 appearance.

A further object of the improvement is to provide a cover of improved construction which will protect the highly-finished parts 25 of the body portion from injury during transportation and which may be taken apart and stowed for future use while using the body portion for book case or shelf.

A still further object of the invention is to provide improved means for securing and 30 locking the cover to the body portion.

The invention consists in the novel construction, combination, and arrangement of parts hereinafter fully described and claimed, and illustrated in the accompanying drawings, 35 to be taken as a part of this specification, and wherein—

Figure 1 is a perspective view of the shipping-box, showing the parts locked together ready for transportation. Fig. 2 is a perspective view of the body portion of the box in use as a book case or shelf, the cover being turned down ready for removal. Fig. 3 is a vertical section taken on the line 3 3 of Fig. 1. Fig. 4 is a horizontal sectional view taken 45 on the line 4 4 of Fig. 2 when the box is in closed position, showing the books in elevation.

The shipping-box consists of two sections, a cover and a body portion or the section 50 thereof to be utilized as a book case or shelf, and is of any suitable form and size or capacity and of a depth sufficient to permit the

books (when two or more body portions are used, as is illustrated in Fig. 2 of the drawings) being tilted upon their lower outer edges 55 without abutting against the bottom of the contiguous shelf to facilitate their withdrawal.

The body portion or shelf consists of a bottom 1, sides 2, and a back 3. The sides 2 are 60 rabbeted at their lower ends for the reception of the ends of the bottom 1 and at their inner edges for the reception of the ends of the back 3, and said pieces are secured together by any proper means. The sides and edges of the 65 body portion which are exposed to view when the same is being used as a book case or shelf are highly polished to lend an artistic appearance thereto.

The cover is adapted to close the body portion and embrace the sides and edges thereof to protect them from injury and prevent the books from having any movement in the box formed by the placing of the cover on the body portion, said cover consisting of a front 70 4, top 5, and sides 6. The sides 6 are constructed of heavy sheet metal, and each has its lower edge and side bent at a right angle to form front and top flanges 4^a and 5^a, respectively, and to which are secured the front 75 4 and top 5. The front 4 and top 5 are each provided in its inner surface at points intermediate its ends with embedded transversely-arranged plates 7, having perforations to align with the slots 8, carrying internally-screwed 80 threaded sleeves 9, which are secured to said plates 7 by screw-bolts 10, terminating at suitable points in the sleeves to permit of the reception of screws 11 from the opposite sides, and which pass through perforations in the 85 flanges 4^a and 5^a to secure the bottom 4 and top 5 to the sides 6. The top 5 is adapted to rest upon the books to occupy the space left to permit them to be tilted, preventing any movement of the books in the box during 90 95 movement or transportation.

It is apparent from the above manner of securing the sections of the cover together that the same may be readily taken apart and stowed when using the body portion for 100 a book case or shelf.

11^a designates straps secured at their ends 12 to the exterior of the back 3 of the body portion and have their outer ends 13 struck

down, forming angle-straps, and adapted to lie flat against the surface of the bottom 1 and to be secured thereto. The ends 13 are provided with elongated slots 14 to receive the hooked ends of angle-irons 15, secured to the bottom 4 of the cover, thus pivotally and detachably securing the cover to the body portion. The ends 12 of the straps have stamped up therefrom perforated ears 16, which fit in recesses formed in the back 3 to place the perforations in alinement with passages 16^a, leading to the edge of said bottom, and which aline with perforations 17 in the flanges 5^a of the cover. Screw-bolts 17^a are passed through said perforations into the passages to place their inner threaded ends in the recess to permit of fastening-nuts being placed thereon to secure the top 5 in position.

The edge 18 is provided with recesses 19, and communicating therewith are longitudinal passages 20, extending through the ends 2 of the body portion and alining with perforations 20^a in the sides 6. Passing through the perforations 20^a into the passages 20, with their inner ends projecting into the recesses, are threaded bolts 21 to permit of fastening-nuts 19^a being placed upon their projecting ends to secure the sides 6 to the body portion, substantially as indicated in Fig. 1 of the drawings.

It is apparent from the above manner of securing the cover to the body portion that the shipping-box is reinforced, and all liability of the contents thereof becoming damaged from any frailness of the box is obviated.

From the foregoing description, taken in connection with the accompanying drawings, it is obvious that the improvement provides a shipping-box which may be converted into a book case or shelf of neat and artistic appearance and which is cheap, durable, and efficient.

Having described my invention, what I claim is—

45 1. In a bookcase and shipping-box, a body portion adapted to be used as a book case or shelf, said body portion being of a depth sufficient to provide a space between the top of the books and the bottom of the contiguous book case or shelf, to permit the books being tilted, straps secured to the body portion, and provided with slots, a cover consisting of sides, a front, and a back, hooks secured to the front and adapted to engage the slots, and means for securing the sides to the body portion.

2. In a bookcase and shipping-box, comprising a body portion adapted to be used as a book case or shelf, said body portion being of a depth sufficient to provide a space between the top of the books and the bottom of the contiguous book case or shelf, to permit the books being tilted, straps secured to the body portion and provided with slots, a cover consisting of sides having top and front flanges, a front and a back, means for securing the front and back to the flanges, hooks secured to the front and adapted to engage the slots, and means for securing the sides to the body portion.

secured to said body portion, to embrace the edges and sides of the body portion to protect them from injury.

3. The combination with a body portion; of a cover consisting of sides having top and front flanges provided with perforations, of a front having perforations, and of a top having perforations, plates having perforations, and secured to said top and front, threaded sleeves mounted in the perforations in the front and top, screw-bolts passing through the perforations in said plates into said sleeves to secure them to the plates, screw-bolts passing through the perforations in the flanges into said sleeves to secure the front, top and sides together, and means substantially as described for securing the cover to the body portion.

4. A shipping-box comprising a body portion having recesses in the back thereof and passages communicating with said recesses and the edge and sides of said back, L-shaped straps secured to said body portion and having perforated ears fitting in said recesses to aline with said passages, and the opposite ends of said straps are provided with slots, a cover provided with perforations adapted to aline with said passages, hooks upon said cover to engage said slots, and screw-bolts passing through said perforations and passages into said recesses, substantially as described.

5. In a bookcase and shipping-box, comprising a body portion adapted to be used as a book case or shelf, and consisting of a bottom, sides and a back, said body portion being of a depth sufficient to provide a space between the top of the books and the bottom of the contiguous book case or shelf, to permit the books being tilted, and a cover adapted to be secured to said body portion and consisting of a top to occupy said space to prevent the books having any movement in the box, a front and sides to embrace the edges and sides of the body portion to protect them from injury.

6. In a bookcase and shipping-box, a body portion adapted to be used as a book case or shelf, said body portion being of a depth sufficient to provide a space between the top of the books and the bottom of the contiguous book case or shelf, to permit the books being tilted, straps secured to the body portion and provided with slots, a cover consisting of sides having top and front flanges, a front and a back, means for securing the front and back to the flanges, hooks secured to the front and adapted to engage the slots, and means for securing the sides to the body portion.
